[57] CLAIM

The ornamental design for a glasses container, as shown and described.

DESCRIPTION

FIG. 1 is a rear elevational view of a glasses container showing my new design, the broken lines shown on the surface of the container throughout the views being understood to represent stitching;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a perspective view of an alternate embodiment of the design shown in FIG. 1, the container being shown in an open condition; and the top and bottom plan views being shown in FIGS. 5 and 6 respectively.

The broken away lines shown in FIGS. 1–7 represent the variable length of the glasses container. The broken lines showing the glasses in FIG. 8 are illustrative only and form no part of the claimed design.
